COLLAPSIBLE BARRICADE

Mike Steinhauer, Appleton, Wis.

Application February 4, 1935, Serial No. 4,918

2 Claims. (Cl. 256—64)

This invention relates to a novel device broadly entitled collapsible barricade and has more specific reference to a portable device expressly designed for street and highway use and intended 5 to be used as a safety semaphore as well as an indicator to show that the street is closed to traffic for some reason or equivalent purpose.

It is a matter of common knowledge that in certain danger zones and so-called quiet zones it 10 is customary for the police and traffic department to use portable signs, pedestals and the like to notify traffic that the street is temporarily closed because of repair work, or for some well deserving reason requiring such safeguarding action.

15 As a general proposition the device most frequently employed is a simple structure including an appropriate base, standard and a sign at the top of the standard containing a proper notification for automobile drivers and the like.

20 The present invention relates to a device which is somewhat in the nature of a collapsible semaphore and which includes a foldable base, a standard and extensible semaphore or signalling arms having the requisite proportions and reach.

25 In reducing the invention to practice and selecting the preferred embodiment thereof, I have evolved and produced a structure which, in my estimation, satisfies the requirements of the trade and possesses such requisites of economy and simplicity as render it susceptible of unqualified endorsement for unlimited use, particularly for 30 street repair work, or in the vicinity of schools as a safety device and so on.

35 Other features and advantages will become more readily apparent from the following description and drawings:

In the drawings:

Figure 1 is an elevational view showing the device set up for street use, said device being extensible to barricade more or less of the entrance of the intersection or street in which it is positioned.

Figure 2 is a top plan view of the arrangement depicted in Figure 1.

Figure 3 is a sectional and elevational view disclosing the construction and arrangement and illustrating in particular the method of folding or collapsing into a compact assemblage.

Figure 4 is a fragmentary perspective of the upper end of the hollow post or column.

Figure 5 is an enlarged detail view taken approximately on the plane of the line 5—5 of Figure 1.

Figures 6, 7 and 8 are sectional views taken on the planes of the lines 6—6, 7—7 and 8—8 re-

spectively, of Figure 1, the devices constituting the base being eliminated in Figure 8.

I call attention first to the standard or column. This is in the nature of a hollow, open-ended sheet metal tube and is indicated by the numeral 9. At the upper end I provide diagonally arranged keeper notches 10 to serve a purpose to be hereinafter described. At the extreme lower end or bottom I provide inwardly projecting stop lugs or ears 11. Adjacent these and in each wall of the standard I provide keeper notches 12. This particular type of a standard is adapted to accommodate or house the projectible and retractile devices or units serving as the supporting base and barrier device.

The base comprises a special slidable fitting which is telescopically arranged within the tubular standard. This is in the form of a weighted metal slide and includes a rectangular frame-like head or collar 13 formed with an integral depending extension 14 which constitutes a mounting or adapter means for the complemental leg or seat 15. There are four of these parts 15 and each one is in the form of an angle iron, the vertical flange being denoted by the numeral 16 and the horizontal flange differentiated by the numeral 17. The flange 16 has an extension 18 which extends into the keeper slot, that is when the device is set up for use, and which extension is pivoted by a bolt and nut as indicated at 19 in Figure 7. With this arrangement, the slide 20 is susceptible of being slipped up into the standard as shown in Figure 3 at which time the legs 15 are collapsed into a cluster-like parallelism. Thus the entire base comprising the slide 20 and the pivotally attached legs can be telescoped or retracted into the enclosing standard. When in use however, the slide or collar 20 drops down by gravity as the legs are pulled out by hand. The pivoted extension 18 rests in the kerfs or keeper notches 12 and occupy horizontal positions extending at right angles to the bottom of the standard and this is sufficient to provide a well-balanced base which will prevent toppling of the barricade as a whole. This extensible and retractile base construction is ingenious in a structure of this type.

Before introducing the extensible and retractile barrier portion of the structure, I would state that this may be made either relatively small as a simple double arm head structure or the arms may be made longitudinally extensible so that they may extend or reach substantially across the mouth of the street in which the barricade is placed. In other words the structure

may be employed on a small scale more or less as an indicator or may be made sufficiently large to serve as an actual barricade. In principle however, the extensible and retractable barrier 5 head comprises a metal follower 21 (see Figure 5) which is in the nature of a metal block and is sufficiently heavy to provide the requisite counter balancing features for the associated arms 22. The follower is actually provided with an up- 10 standing central shank or attaching member 23 and it is to this that the inner ends of the arm are pivotally attached by a single bolt as indicated at 24. Metal wear plates or shields of channel shaped cross section indicated at 25 are 15 fastened by screws or the like 26 to the inner pivoted ends of the wooden arms 22. This provides for requisite longevity or durability. When not in use the arms fold with the follower into the standard as shown in Figure 3. When in use 20 they extend at right angles out through the keeper notches 10 as illustrated in Figure 1. The arms are actually composed of inner and outer sections 27 and 28, the inner section having a rib 29 and the outer one being formed with a groove 25 to receive it. The rib and groove arrangement may be of the dove-tail form illustrated in Figure 6. A connecting bolt and nut 30 serves to join the sections together in extensible relationship. Thus we have a pair of arms of longitudinally extensible type having wear plates at their 30 inner ends pivotally attached as at 24 to the stem portion 23 of the counterbalancing follower or mounting unit 21. Obviously, then the arms can be adjusted as requirements dictate to employ 35 the device as a simple caution sign or as an actual street barrier or barricade.

It is believed that the idea of a hollow standard having the extensible and retractable base

and head units of the construction herein illustrated and described is ingenious and sufficient to serve the purposes for which the invention is intended.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details coming within the field of invention claimed may be resorted to in actual practice, if desired.

Having thus described the invention, what is claimed as new is:

1. In a structure of the class described, a collapsible base, a standard rising from said base, barrier arms attached to the upper end of said standard, a hollow standard, a slide mounted in 20 said standard, a plurality of legs pivotally attached at their inner ends to said slide, said legs being collapsible into the standard when not in use and extensible at right angles to said standard when in use to serve as a base for said 25 standard.

2. In a structure of the class described, a hollow standard notched at its bottom and provided adjacent said notches with stop lugs, a collar 30 slideable in said standard, a plurality of angle irons pivotally attached at their inner ends to said collar and cooperable with said notches and lugs in the manner and for the purposes described, and a slideable fixture in the upper portion of the standard, and barrier arms pivotally attached at their inner ends to said fixture and foldable into the standard when not in use.

MIKE STEINHAUER.
